UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

DESIGN FOR A PHONOGRAPH-CABINET.

56,643.

Specification for Design.

Patented Nov. 16, 1920.

Application filed September 10, 1919. Serial No. 323,035. Term of patent 14 years.

To all whom it may concern:

Be it known that I, JOSEPH WOLFF, a subject of His Majesty the King of Great Britain, residing in the borough of Brooklyn, county of Kings, city and State of New York, have invented a new, original, and ornamental Design for Phonograph-Cabinets, of which the following is a specification, reference being had to the accompanying drawings, forming a part thereof. This figure is a perspective view of a ph-

nograph cabinet illustrating my improved design.

I claim:—

The ornamental design for a phonograph cabinet, substantially as shown.

This specification signed and witnessed this 28th day of July, 1919.

JOSEPH WOLFF.
